MULTIPLE ATTACHMENT RECEPTACLE

Herman C. Lee and Ralph Forbush Norris, Madison, Wis., assignors to C. F. Burgess Laboratories, Inc., Madison, Wis., a corporation of Delaware

Application July 8, 1932, Serial No. 621,432

14 Claims. (Cl. 247—28)

This invention relates to improvements in multiple attachment receptacles or outlets for supplying electrical energy to current consuming appliances. More particularly the invention relates to an improved structure wherein relatively long conductors are concealed in the baseboard along the wall of a room, are connected to the lighting supply circuit and are connected also, at frequent or desired intervals along their length to attachment plug receptacles which are exposed in the baseboard and to which attachment plugs, with flexible conductors extending therefrom, may readily be connected. The construction is adapted to provide receptacles at sufficiently frequent intervals, or to readily permit the installation of additional receptacles in sufficient number, so as to provide available electric energy outlets at substantially any desired point within a room.

Devices as heretofore proposed for this purpose usually involve the employment of slots extending throughout substantially the length of the baseboard with current carrying conductors exposed within the slots. The slots were necessarily of substantial width, and were unsightly and caught dust and dirt and also water during scrubbing and mopping operations. They also afforded opportunity for immature persons to insert wire or metal objects therein, thus presenting risks of short circuits. These devices, furthermore, were complicated, expensive and difficult to install. In order to conceal the construction as much as possible, special baseboard constructions were used and in some instances they were installed in connection with the moldings from which pictures were hung. Special attachment plug caps were required and such special equipment, of course, rendered the constructions conspicuous which is a result to be avoided. Constructions involving the use of spaced receptacles were very few and were subject to the same objections. In these constructions, after the locations of the receptacles were fixed, they could be changed or additional receptacles installed only with difficulty.

The object of the present invention is to provide a multiple attachment receptacle which permits the employment of ordinary baseboards and the insertion of the receptacle construction between upper and lower sections of the baseboard in an easy and ready manner.

It is another object of the invention to provide an improved multiple attachment receptacle in which the construction is concealed from view and there is presented to view what appears to be substantially the plain, continuous surface of

the baseboard with a scarcely distinguishable plug receptacle, flush with the surface of the baseboard and having, as the most noticeable feature, a pair of slots adapted to receive the small, flat contacts of an attachment plug cap.

It is a further object of the invention to provide an improved multiple attachment receptacle which does not have its continuity broken at the corners of the room and which is inexpensive, comprises a minimum number of parts, is permanent for all practical uses and still permits ready access to the internal parts for repairs and changes and also permits the ready change of location or increase in number of receptacles.

It is a further object of the invention to provide an improved multiple attachment receptacle of the character mentioned which does not catch dust and dirt and which prevents the entrance of water during scrubbing or mopping operations.

The preferred embodiment of the invention may be described, briefly, as comprising an elongated channel fitted between upper and lower sections of a baseboard, within which channel a pair of conductors is disposed longitudinally and is connected at desired intervals to blocks of suitable insulating material or so-called shaped receptacles, suitable for the insertion of the flat contacts of an ordinary attachment plug cap. The receptacles fit transversely within the channel, that is, they fill the space between the side walls thereof. Cover sections close the portions of the channel between receptacles to form a closed conduit with the surface of said receptacles exposed at intervals. Portions of the cover sections preferably overlie contiguous portions of the receptacles to maintain the latter in place. The exposed surfaces of the cover sections and of the receptacles are flush with each other and also with the surface of the baseboard to present a uniform, inconspicuous and attractive appearance.

In the drawings:

Fig. 1 is a front elevation of a portion of the improved multiple attachment receptacle;

Fig. 2 is a perspective view of a moulded socket member of insulating material, showing its relation to the parallel conductors;

Fig. 3 is an enlarged transverse sectional view along line 3—3 of Fig. 1;

Fig. 4 is an enlarged longitudinal sectional view along line 4—4 of Fig. 1;

Fig. 5 is an enlarged transverse sectional view along line 5—5 of Fig. 1;

Fig. 6 is an enlarged transverse sectional view along line 6—6 of Fig. 1;

Fig. 7 is a perspective view of a sheet metal contact member which forms part of each receptacle;

Fig. 8 is a transverse sectional view along line 8—8 of Fig. 1 showing one method of connecting our improved multiple attachment receptacle to a source of electrical energy;

Fig. 9 is a perspective view of a connecting member suitable for connecting successive running sections of the channel, which forms the rear portion of the enclosure of the improved multiple attachment receptacle;

Fig. 10 is a perspective view of one form of cover member;

Fig. 11 is a top view of special forms of channel and cover members adapted for use at corners;

Fig. 12 is a partial front view of a modified form of improved multiple attachment receptacle;

Fig. 13 is a transverse sectional view along line 13—13 of Fig. 12; and

Fig. 14 is a partial front view showing a receptacle having a special or modified shape.

Referring to Figs. 1 and 3, the general arrangement of the multiple receptacle is shown. Upper and lower baseboard sections 10 are separated vertically a distance equal to the width of the conduit which is indicated generally by numeral 11, and which, as illustrated more in detail hereinafter, comprises an elongated channel, i.e., a base and side flanges with an open top, or, when said channel is mounted, as shown in Fig. 3, with an open front side which may be closed by cover sections, equal in length to the desired distance between receptacles and adapted to snap into engagement with the channel flanges. The channel and cover sections are preferably formed from sheet metal. At desired points along the length of the conduit there are exposed receptacles 12 of insulating material, carrying terminals to which insulated conductors 13 are connected within said conduit. A portion of said conduit is shown at which an entrance is provided for electric energy supply conductors 14 which are connected to said conductors 13. The connections will be described and illustrated more in detail hereinafter.

In Fig. 2, the preferred shape and design of the socket member 15 of receptacle 12 is shown from the rear. Said member may be made of suitable insulating material such as porcelain, hard fiber or a phenol condensation product (bakelite), preferably the latter. Within the rearward portion of said member there are two parallel and oppositely disposed longitudinal grooves 16 with communicating, substantially rectangular recesses 17 in the intervening septum and removed a short distance from said recesses, in the direction toward the opposite ends of grooves 16 are ridges or partitions 18, which partially close said grooves. At opposite ends of member 15 are indentations 19 and along the sides of said member are ribs or flanges 20. The purposes of grooves 16, recesses 17, partitions 18, indentations 19 and flanges 20 will be explained hereinafter.

In Fig. 3, the conduit 11 is shown more in detail and comprises elongated channel members 21, i. e. substantially U shaped in cross section, and a plurality of substantially U shaped cooperating cover sections or channel members 22, although a cover long enough to span several socket members with openings therein to expose said socket members, may be employed. The side

flanges of said channel members 21 are offset inwardly, as shown, and are provided with outwardly extending points or ribs 23. The side flanges of the cover sections 22 are doubled back upon themselves to form inner ledges 24. The vertical spacing between baseboard sections 10 may be approximately equal to the greatest width of channel member 21 or preferably slightly greater, whereby the latter may be readily inserted in said space and secured to the wall by means of screws 25, for example. Conductors 13 and socket members 15, with contacts attached, may be inserted in channel member 21 and connected as will be described more in detail hereinafter. As shown in Fig. 3, each socket member 15 fits snugly between the offset portions of the side flanges of channel member 21. Cover sections 22 may then be pushed inwardly. The lateral sides of member 21 may be offset a distance equal to twice the thickness of the material of which the cover sections 22 are made. The sides of cover sections 22 enter the space between the baseboard sections and the side walls of channel member 21 and, when passing over the small projections or points 23, compress the sides of member 21 toward each other slightly. This is possible because cover sections 22 are located between receptacles 12 and compress only the portions of channel member 21 which have the projections 23 thereon. See Fig. 4. When the doubled portions of the sides of cover sections 22 pass said projections 23, the sides of the channel member snap back into place and the exterior surfaces of the latter and of the sides of cover 22 are substantially flush with each other and cover 22 is locked in place.

Fig. 4 illustrates the manner in which the receptacle is held in place in the channel of member 21. The former fits snugly between the side walls of the channel as stated and the end portions thereof are shouldered at 26 to permit the end portions of cover sections 22 to fit over the same and lock the receptacle in place. The insulation is removed from a short portion of conductor 13 where it passes through the rear groove 45 in the receptacle. A sheet of insulating material 27 covers the rear of receptacle 12 and may be held in place by a spring metal clip 28, the end portions of which engage the recesses 19 in the ends of said receptacle. The insulating sheet 50 27 may be slightly longer than the rear portion of said receptacle and the clip 28 may be looped around the end portions of sheet 27, so that the sheet and its clip may be handled as a unit.

As shown by Figs. 3 and 4, for practical purposes cover 22 is held permanently in place upon channel member 21, and receptacle 12 is similarly held in place by cover 22. However, if it is desired to remove a section of cover 22 in order to get at the interior of the channel, an edged tool 60 such as a screw driver can be inserted between the end of cover 22 and receptacle 12 and upon the cover being pried away from channel 21, the doubled portions of its sides pass over projections 23 without great difficulty, after which the cover 65 can readily be removed.

Figs. 5 and 6 show how flanges 20 of receptacle 12 overlie the edges of the channel flanges and fill in the space between base board sections 10, to present a substantially flush and continuous 70 surface between cover sections 22. Figs. 5, 6 and 7, in conjunction with Fig. 4, illustrate the manner in which a circuit is established between the conductors 13 and the thin flat contacts of an ordinary attachment plug cap. The insulation 75

is removed from the conductors from partitions 18 to a point beyond recesses 17. Substantially A-shaped spring metal strip contacts 35, (see Fig. 7) are mounted in receptacle 12 with the cross of each A contact resting against the innermost surface of recesses 17 and the leg portions of the A contacts disposed within recesses 36 which communicate by slots 37 with the front surface of the receptacle. Conductors 13 are in contact with the lower surfaces of the crosses of the respective contacts and are held in firm contact therewith by means of screws 38 which are adapted to be screwed into threaded openings 39 of strips 35. Conductors 13 preferably are held in the angles formed by the junction of the crosses with the legs of the contacts, as shown in Fig. 6. Recesses 40 are provided to accommodate the stems of screws 38.

Fig. 5 shows the thin flat contacts 41 of an attachment plug cap 42 about to be inserted into slots 37 and into electrical contact with strips 35. The partitions 18 insure that the insulation upon conductors 13 does not extend into recesses 36 and impair the contact of members 39 with the strips 35 (see Fig. 2).

If desired, conductors 13, with receptacles 12 attached at predetermined intervals, corresponding with the length of cover sections 22, may be made up at the factory. However, said cover sections may be made up in different lengths and in fact, may be cut by the electrician on the job and it promotes flexibility in accommodating the improvements to different conditions with respect to locating the receptacles at desired points, to have the receptacles attached to the conductors on the job. The conductors may be disposed more or less loosely within the channel so that they may be pulled forwardly a sufficient distance to be worked upon conveniently by the electrician. The insulation may then be removed from short portions and these portions disposed in the grooves 16 of the receptacles 12 and contact strips 35 connected thereto. Rear cover sheets 27 may then be applied by means of the clips 28 and the receptacle introduced into the proper place within the channel 21. The fact that conductors 13 are loose within said channel permits the necessary longitudinal adjustment of said receptacles for positioning the same properly with respect to the ends of cover sections 22.

Fig. 8 illustrates one method of connecting conductors 13 to a source of electric energy. Opening 45 may be provided in the rear of channel 21 at some point where supply conductors 14 are available. Into this opening connector 46, 47 may be fastened for anchoring to the channel member 21, the end of the conduit 48 through which the supply conductors 14 pass. With cover 22 removed, conductors 13 may be drawn out of channel 21 and the insulation removed from portions of their length and also from the end portions of conductors 14 and said conductors 13 and 14 connected and taped up in the usual fashion. The excess of conductors 14 may be folded into channel 21 and cover 22 may be snapped into place.

In the ordinary wiring of base plug outlets, an outlet box is usually located in the wall corresponding to the location of the base plug, and wires are connected between the outlet box and the base plug. The same method may be employed with this multiple receptacle. An outlet box may be installed in the wall and conductors 13 may be led through the opening 45 and connected at their ends to the conductors in the

outlet box. In this method of connection two sets of conductors 13 may be employed, each set extending in an opposite direction from the outlet box.

A convenient means for connecting successive running sections of channel 21 is illustrated in Fig. 9. Connecting member 50 is shaped to fit telescopically within channel 21, preferably sufficiently tight to provide friction such that considerable strength is required to effect relative movement with the hands. An indentation 51 is punched into the interior surface of the connecting member approximately centrally between its ends. The projection thus created engages the end edge of channel 21 and when the next channel is forced over member 50 the latter will be located substantially centrally between the two.

Fig. 10 illustrates a special cover member 52 for channel 21 which has advantages for particular applications. It is similar to cover 22 except that its front side 53 has extensions 54 at its ends. Extensions 54 are offset outwardly a distance substantially equal to the thickness of the material of which the covers are composed. As an example of a use for cover member 52, it may not be desirable to provide receptacles between all cover sections 22. In such case cover member 52 may be of the same length as a receptacle and may be inserted between cover sections 22, at points where receptacles are not wanted and extensions 54 will overlie the adjacent ends of cover sections 22. Then, if at any future time, the householder wishes a receptacle at a new location the electrician can remove cover member 52 by inserting a screw driver between extensions 54 and the end of the adjacent cover section 22 and prying member 52 off the channel. The adjacent ends of cover sections 22 may then be pulled outwardly a short distance. The insulation may be removed from portions of conductors 13 and a receptacle connected thereto and inserted in channel 21 and the ends of cover sections 22 snapped back into place.

Fig. 11 illustrates a corner construction which makes it possible to maintain electrical continuity along two or more walls of a room. An external corner, or what may be termed a 270° corner construction is illustrated but it is obvious that an internal corner or 90° corner or any other angle construction may be employed as needed. Angular channel member 56 has the same shape in cross section as channel 21 and is adapted to be aligned with and connected to the straight channel sections by means of connectors 50 such as shown in Fig. 9. Angular cover member 57 has the same sectional shape as cover sections 22 and is adapted to snap over channel member 56, which, in the form shown, has its open side facing outwardly. Cover member 57 may have offset end extensions 58 similar to extensions 54 upon cover member 52. Since cover sections 22 usually must be cut to length on the job in order that they may terminate at the corners of the room, an irregular end may result and extensions 58 serve to conceal such irregularities. It is obvious that conductors 13 may be concealed in and extend continuously around a corner where a construction of this character is used.

In the modification of our improved multiple attachment raceway illustrated in Figs. 12 and 13, the channel member 21 is employed just as in the forms described heretofore. Cover 61 is

U-shaped in transverse section and adapted to snap over the sides of channel member 21. The cover 61 may be of indefinite length and be provided at convenient intervals, such as from one foot to six feet, for example, with partially severed circular portions 62 in much the same manner that knock-outs are provided in ordinary electrical outlet boxes. Numeral 63 indicates the line along which the material of cover 61 may be cut and partially severed. This may be done by means of a suitable punch operating upon the rear surface of the covers. Of course portion 62 may be of any suitable shape, and at those points where receptacles are desired, portions 62 may be removed by a blow with a hammer. At these points the insulation may be removed from short portions of conductors 13 and receptacles 64 may be connected thereto. Each receptacle has a shoulder 65, shaped to accommodate the material of cover 61 immediately adjacent an opening formed by the removal of portion 62 and this holds said receptacle in place and presents a substantially flush exposed surface. It is apparent that this latter modification is also adapted for the ready installation of additional receptacles as they are desired.

Fig. 13 also shows a different method of attaching contact strips 66 to conductors 13. Recesses 67 are provided for the accommodation 30 of contact strips 66 and communicate with the exposed surface of receptacle 64 by means of slots 68. The insulation is removed from short portions of conductors 13 and one end of each contact strip 66 is bent around said conductor 35 before said contacts are assembled in the insulating block. The connection may be made permanent by applying solder to the joint. This form of connection is more particularly adapted to a construction where the receptacles are attached 40 to the conductors at the factory.

While receptacles of square and circular shapes have been described thus far, it is apparent that other shapes may be employed. Fig. 14 illustrates an hexagonal receptacle 72 between cover 45 sections 73 which have their ends cut at angles so that they fit over the ends of the receptacle. In the same manner any desired special shape of receptacle may be used with a long cover or short cover sections.

50 This improved multiple attachment receptacle is not limited to use in connection with baseboards. It possesses the important advantage that channel members 21 may be quickly and easily applied to any surface, by means of screws 55 or other fastening means, such as nails. The construction lends itself, therefore, to rapid or temporary installations, as for display illumination, exhibition booths, and the like. It will be understood that the terms "upper", "lower", "forward", "rear" and similar terms are used in the 60 claims to indicate the relative arrangement of certain parts and thus facilitate the description rather than being used in a limiting sense.

We claim:

65 1. In a multiple attachment receptacle, a substantially continuous elongated channel, a pair of conductors extending longitudinally within said channel and insulated from one another, shaped attachment plug sockets disposed at intervals 70 along the length of said channel intermediate the ends thereof, and attached to said conductors, said sockets being insertable laterally into said channel, the rear and side surfaces of said sockets resting against the rear and side walls of said 75 channel, laterally extending shoulders on said

sockets overlying the edges of the side walls of said channel, cover sections fitting over said channel and having means coating with the side walls thereof pressing said sockets in place.

2. In a multiple attachment receptacle, 5 an elongated channel, the marginal portions of the sides of said channel being off-set inwardly, shaped attachment plug sockets disposed at intervals along the length of said channel intermediate the ends thereof, said sockets being insertable laterally into said channel and fitting between the interior surfaces of said offset portions, cover sections having side flanges fitting over and engaging said offset marginal portions and closing the open side of said channel between said sockets, 10 the exposed surfaces of the sides of said channel and said cover sections being substantially flush with one another and the end portions of said cover sections fitting over the end portions of said sockets and pressing said sockets in place in 15 said channel.

3. In a multiple attachment receptacle, an elongated channel, the marginal portions of the sides of said channel being offset inwardly, longitudinally spaced outward projections on said offset 20 portions, shaped attachment plug sockets disposed at intervals along the length of said channel intermediate the ends thereof, said sockets being insertable laterally into said channel and fitting between the interior surfaces of said offset 25 portions, cover sections substantially U-shaped in transverse section, fitting over said offset marginal portions and closing the open side of said channel between said sockets, the margins of the sides of said cover sections being doubled back 30 inwardly to provide ledges, said ledges engaging said projections to hold said cover sections in place and the end portions of said cover sections fitting over the end portions of said sockets and pressing said sockets against said channel to lock 35 40 said sockets in place in said channel.

4. In a device of the class described, a pair of insulated conductors, attachment plug sockets attached to said conductors at intervals along the length thereof, said sockets each comprising a 45 body of insulating material of uniform width to fit within a hollow molding, said body having recesses with openings from said recesses to a surface thereof, plug contacts within said recesses each comprising a one-piece substantially A-shaped flat spring metal strip with a threaded 50 opening in the cross member, said conductors being held in contact with said strips by means of screws threaded into said openings, said strips being adapted to provide spring contact with the 55 contacts of an attachment plug cap insertable through said openings in said body.

5. In a device of the class described, an attachment plug socket comprising a body of insulating material of uniform width to fit within 60 a hollow molding, having flanges adapted to overlie the edges of said molding and having grooves in a surface thereof adapted for the accommodation of conductors passing therethrough and having recesses in the ends thereof, a rear 65 closure for said grooves comprising a sheet of insulating material slightly longer than said socket and a spring metal clip looped about the end portions of said sheet and having its ends engaged in said recesses.

6. A device of the class described comprising, in combination, an elongated channel having a rear wall and side walls, the forward side thereof being open, said side walls having substantially 70 parallel interior surfaces, an attachment plug 75

socket fitting between said parallel surfaces, and being slidable rearwardly into said channel, and a cover clamping over said side walls and engaging said socket and pressing said socket into said channel.

7. A multiple attachment receptacle comprising, in combination, an elongated channel having a rear wall and side walls, the forward side thereof being open, attachment plug sockets disposed at intervals along the length of said channel and fitting between said side walls, a cover fitting over said side walls and having clamping engagement therewith, said cover engaging forward surfaces of said sockets and pressing said sockets into position in said channel.

8. A device of the class described comprising, in combination, an elongated channel having a rear wall and side walls, the forward side thereof being open, an attachment plug socket disposed within said channel and fitting between said side walls, said socket being slidable rearwardly into said channel and into seating engagement with a surface of said channel, and cover sections clamping over said side walls and pressing said socket against said seating surface.

9. A multiple attachment receptacle comprising, in combination, an elongated channel having a rear wall and side walls, the forward side thereof being open, attachment plug sockets disposed at intervals along the length of said channel, said sockets fitting within said channel and being slidable rearwardly thereinto, and a clamping member having latching engagement with said side walls and pressing said sockets into said channel, said clamping member comprising a cover for said channel closing said open side thereof between said sockets.

10. A device of the class described comprising, in combination, an elongated channel having a rear wall and side walls, the forward side thereof being open, an attachment plug socket disposed within said channel, said socket being insertable rearwardly into said channel, and having side walls fitting within the side walls of said channel, and having marginal flanges overlying the edges of said side walls, a cover fitting over said channel and having clamping engagement with said side walls, said cover having an opening therein through which said socket is exposed, the material of said cover adjacent said openings engaging marginal forward portions of said socket to press said flanges against said side wall edges.

11. A device of the class described comprising an elongated channel having a rear wall and side

walls, the forward side thereof being open, a one-piece attachment plug socket disposed within said channel and fitting between said side walls, said socket being slidable rearwardly into said channel and having marginal flanges engaging the edges of said side walls, and cover sections clamping over said side walls, end portions of said cover sections engaging end portions of said socket and pressing said flanges against said side wall edges.

5

12. A multiple attachment receptacle comprising, in combination, a wall, upper and lower baseboard sections attached to said wall and spaced apart vertically, an elongated channel between said baseboard sections, said channel having a rear wall and side walls, the forward side thereof being open and disposed away from said wall, attachment plug sockets disposed at intervals along the length of said channel, said sockets fitting between said side walls, and a cover fitting over said side walls and having clamping engagement therewith, said cover engaging forward surfaces of said sockets and pressing said sockets into position in said channel.

10

13. A multiple attachment receptacle comprising, in combination, a wall, upper and lower baseboard sections attached to said wall and spaced apart vertically, an elongated channel between said baseboard sections, said channel having a rear wall and side walls, the forward side thereof being open and disposed away from said wall, attachment plug sockets disposed at intervals along the length of said channel, said sockets fitting between said side walls and being slidable rearwardly into said channel, cover sections having side flanges fitting over said channel side walls and having latching engagement therewith, the end portions of said cover sections fitting over the end portions of said sockets and pressing said sockets into position in said channel.

15

14. A multiple attachment receptacle comprising an elongated channel having a base and parallel side walls, attachment plug sockets having parallel side walls and of a width to frictionally engage said channel side walls whereby said sockets may be inserted in said channel at intervals longitudinally in contact with the base and side walls thereof, and a cover having flanges fitting over said channel side walls to hold it in place, said cover confining said sockets in said channel and maintaining their longitudinal spacing.
